CLAIM

We claim an ornamental design for a trash bag drawstring with a repeated pattern, as shown and described.

DESCRIPTION

FIG. 1 is an isometric front view of a trash bag drawstring with a repeated pattern in accordance with the invention;

FIG. 2 is a front view thereof;

FIG. 3 is a left side view thereof;

FIG. 4 is a rear view thereof;

FIG. 5 is a right side view thereof; and,

FIG. 6 is a top view thereof.

The drawings depict a trash bag drawstring of translucent plastic material.

The regular dash-dot broken line showing of portions of the claimed design is included for the purpose of illustrating environmental structure and forms no part of the claimed design.

The dash-dot-dot broken lines are included to show the bag to which the drawstring is applied and forms no part of the claimed design.
